UNITED STATES PATENT OFFICE.

WALTER T. BOBO, OF BATTLE CREEK, MICHIGAN, ASSIGNOR TO THE EASY TRUSS COMPANY, OF BATTLE CREEK, MICHIGAN.

TRUSS-PAD.

Specification of Letters Patent.

Patented Jan. 9, 1917.

1,211,666.

Application filed July 10, 1916. Serial No. 108,332.

To all whom it may concern:

Be it known that I, WALTER T. BOBO, a citizen of the United States, residing at Battle Creek, county of Calhoun, State of Michigan, have invented certain new and useful improvements in Truss-Pads, of which the following is a specification.

This invention relates to improvements in truss pads.

10 The main object of this invention is to provide an improved truss pad which can be inflated to secure the desired degree of resiliency and one which is simple and economical in its parts.

15 Further objects, and objects relating to structural details, will definitely appear from the detailed description to follow.

I accomplish the objects of my invention by the devices and means described in the 20 following specification.

The invention is clearly defined and pointed out in the claims.

A structure which is a preferred embodiment of my invention is clearly illustrated 25 in the accompanying drawing, forming a part of this specification, in which:

Figure I is a front perspective view of the pad proper. Fig. II is a rear view with the attaching straps in position. Fig. III is an 30 enlarged detail section on a line corresponding to the broken line 3—3 of Fig. II. Fig. IV is a detail view of the front end of the attaching strap. Fig. V is a rear perspective view of the pneumatic container.

35 In the drawing similar reference characters refer to similar parts throughout the several views.

Referring to the drawing, my improved pad comprises a rubber casing 1 of suitable 40 conformation having an opening 2 in the rear wall thereof, the rear wall of the casing being flat. Within the casing is a thin rubber inner container 3 provided with an air valve 4 secured by a valve plate 5. I arrange 45 an inner plate 6 within the casing, the plate having an annular groove 7 adapted to receive an internal annular rib 8 on the rear wall (see Fig. III). This inner plate also has threaded bosses 9 adapted to receive 50 the attaching screws 10 which are disposed through an outer plate 11 and the attaching strap 12. These plates and strap have registering holes adapted to receive the valve 4 and the strap has elongated holes 13 adapted 55 to receive the attaching screw. The pur-

pose of the elongated holes is to permit the adjustment of the angle of the strap relative to the pad; as, when the screws 10 are loosened the strap may, for purposes of adjustment, be swung to a limited extent about 60 the stem 4. The casing is preferably provided with a covering 14 of silk or other suitable material. The edges of this covering are drawn over the rear wall of the casing and clamped between the casing and 65 the strap 12. Thus the parts are effectively secured by means of the screws 10. The screws 10 are preferably provided with collars 15 so that their outer ends constitute studs 16 for the strap couplings 17 which 70 have inner slots 18 therein, as shown in Fig. II. The valve 4 is provided with a cap 19. The covering 14 may be quickly renewed as occasion requires. The strap 12 is provided with a buckle 20 for the supporting belt 21. 75 The other end of the belt 21 is secured to the coupling member 17. The crotch strap 22 is provided with a coupling member 23.

I have described the container as being an air container but it may be filled with a 80 liquid, such as water or oil.

With the parts thus arranged the pneumatic container may be inflated to the desired extent to produce the desired rigidity or flexibility of the pad. The parts are so 85 shaped and arranged that they are economical to produce and easily and quickly assembled.

Having thus described my invention, what I claim as new and desire to secure by Letters Patent, is:

1. In a truss pad, the combination of a rubber casing having an opening in its rear wall, an inner container disposed within said casing and provided with a valve, an 95 inner closure plate disposed within said casing to overlap the edges of the opening in the rear wall thereof, a fabric casing covering having its edges drawn over the rear wall of said covering, a supporting strap disposed over said covering, an outer closure plate disposed over said strap, said plate and strap having registering openings through which said valve projects, and screws disposed through said outer plate and strap and 100 threaded into said inner plate whereby the parts are secured together and the inner wall of the casing closed, said strap being provided with openings for permitting the 105 adjustment of the strap.

2. In a truss pad, the combination of a rubber casing having an opening in its rear wall, an inner container disposed within said casing and provided with a valve, an inner closure plate disposed within said casing to overlap the edges of the opening in the rear wall thereof, a fabric casing covering having its edges drawn over the rear wall of said covering, a supporting strap disposed over said covering, an outer closure plate disposed over said strap, said plate and strap having registering openings through which said valve projects, and screws disposed through said outer plate and strap and threaded into said inner plate whereby the parts are secured together and the inner wall of the casing closed.
3. In a truss pad, the combination of a rubber casing having an opening in its rear wall, an inner container disposed within said casing and provided with a valve, an inner closure plate disposed within said casing to overlap the edges of the opening in the rear wall thereof, a fabric casing covering having its edges drawn over the rear wall of said covering, a supporting strap disposed over said covering, an outer closure plate disposed over said strap, said plate and strap having registering openings through which said valve projects, and screws disposed through said outer plate and strap and threaded into said inner plate whereby the parts are secured together and the inner wall of the casing closed.

threaded into said inner plate whereby the parts are secured together and the inner wall of the casing closed, said screws being provided with collars spaced from their heads 35 so that the screws constitute attaching studs.

4. In a truss pad, the combination of a rubber casing having an opening in its rear wall, an inner container disposed within said casing and provided with a valve, an inner closure plate disposed within said casing to overlap the edges of the opening in the rear wall thereof and having outwardly projecting internally threaded bosses, a fabric casing covering having its edges 45 drawn over the rear wall of said covering, a supporting strap disposed over said covering, an outer closure plate disposed over said strap, said plate and strap having central registering openings through which said 50 valve projects, and screws disposed through said outer plate and strap and threaded into said bosses of said inner plate whereby the parts are secured together and the inner wall of the casing closed.

In witness whereof, I have hereunto set my hand and seal in the presence of two witnesses.

WALTER T. BOBO. [L. s.]
